UNITED STATES PATENT OFFICE.

GEORG ANDREAS HEINRICH BOLLMANN, OF HAMBURG, GERMANY.

JET-WASHING APPARATUS.

Application filed December 22, 1923. Serial No. 682,262.

To all whom it may concern:

Be it known that I, GEORG ANDREAS HEINRICH BOLLMANN, a citizen of Germany, residing at Hamburg, Gertrudenkirchhof 21, 5 Germany, have invented certain new and useful Improvements in a Jet-Washing Apparatus, of which the following is a specification.

In filters working with granular filter materials, such as sand, gravel and the like, it is necessary now and then to clean or wash the filter material, which is carried out by the aid of jets of water or other washing liquid that is squirted into the filter material by the aid of one or more nozzles. It has been frequently observed that, as soon as the compressed washing liquid is shut off, sand or other filter material passes by way of the nozzle into the feed pipe for the compressed liquid. To obviate this inconvenience divers means have been proposed. Conical or otherwise shaped screens, forming a sort of filter-sieve, have been arranged within the feed pipe near the jet nozzle to hold back any granular filter material, that might tend to enter the feed pipe through the nozzle. These means however have not fully answered their purpose, and now and then a choking up of the feed pipe happened. Particularly for large filters, in which the pressure of the sand against the mouth of the nozzle is considerable, the described drawback was found to be very serious. Neither jet washing apparatus of such description, in which between the nozzle and the feed pipe proper a sand seal is formed by the filter material itself which seal is pressed away on the compressed liquid being turned on, and which on shutting off the compressed liquid is again created by the weight of the filter material, nor jet washing apparatus in which a dish shaped sand trap within the nozzle pipe is arranged for catching up the returning sand in such manner, that the narrow space between the nozzle opening and the dish becomes clogged in order to prevent a further entering of sand into the feed pipe, operate by any means with sufficient reliability, since the danger of the accumulating sand within the sand seal or on the dish shaped sand trap increasing to such an extent that some of it nevertheless enters the feed pipe, is by no means removed.

The object of the present invention is to construct a jet washing apparatus which is

well adapted even for the largest filters. With this object in view a valve is provided within the feed pipe, adapted to shut the nozzle carried by the end of the feed pipe. 60 This valve is preferably cone shaped and is connected with a valve rod, passing with its upper end through a dish shaped sand trap. The conical valve is of sufficient length to reach with its vertex approximately up to the mouth of the nozzle when in open position. The lower end of the nozzle, forming the seat of this valve, is rounded off at its rim, and by these means together with the shape of the cone a perfect closure is attained, even if large amounts of sand rest on the mouth of the nozzle. The amount of sand, passing the valve on its movement, is very small and does not change to any degree worth speaking of. The sand trap, once given the proper dimensions, takes up the surplus of the sand under all working conditions and thus prevents any of the filter material from passing into the feed pipe. 80

The rod carrying the valve passes through a stuffing box in the wall of the bend forming the end of the feed pipe and is here connected with a double armed lever movably fulcrumed outside of the pipe and 85 adapted to be oscillated by hand or otherwise.

When the filter is out of use for a long time it might happen, that the conical valve will not be sufficient to loosen the mass of sand, bearing against it, and special means may be provided for stirring up the sand. The invention therefore provides such means consisting of a cylindrical perforated mantle surrounding the end of the feed pipe, carrying the jet nozzle and forming an annular space around the said end of the feed pipe. A conduit connecting the said space with the interior of the feed pipe or with an auxiliary pipe allows compressed liquid to enter the said annular space, which liquid passes out through the perforations of the said mantle to act on the sand accumulated around the extreme end of the feed pipe, thus stirring it up and assisting the 100 conical valve in its operation.

In the drawing a section of the jet washing apparatus is shown adapted to wash filter material used in sand filters or the like.

The feed pipe is shaped as an elbow 1 carrying at its upper end a dome 2 with a

nozzle 3. The lower opening of this nozzle is rounded off at the edge to form a seat for the cone shaped valve 4. The valve rod 6 on this valve passes through a dish shaped sand trap 5 arranged below the nozzle 3 to guide the valve centrally to the nozzle, the valve being of such length as to project with its vertex into or approximately up to the mouth of the nozzle. Owing to the lower end of the nozzle being rounded off, the valve in closed position will contact with the thus formed seat only in a line. At its lower end the valve rod 6 passes through a stuffing box formed on the wall of the elbow. The outer projecting end of the valve rod is pivotally connected at 8 with a double armed lever 9 having a handle 19 at its free end, a pivot pin 10 of which passes through the end of a link 12 which is pivotally connected with a bracket 11. The valve 4 is closed by moving the lever 9 downwards by its handle before the compressed washing liquid is shut off. The nozzle 3 and dome 2 are embedded in the filtering material.

The dome shaped end 2 of the feed pipe is surrounded by a cylindrical perforated mantle 13 forming an annular space 20, which by the aid of a conduit 15 is adapted to communicate with the interior of the bend 1 and with auxiliary water feed pipes 16. The perforations of the mantle 13 are preferably created by punching out inclined nose shaped protuberances 14 to prevent sand from entering the annular space 20. The opening 17 of the conduit 15 can be closed by a valve 21, if it is not desired to allow compressed liquid to enter the space 20 from the bend 1. When the liquid enters the annular space 20 it runs out through the nose like openings 14 and loosens the sand above the nozzle 3.

I claim:

1. A jet washing apparatus for filters comprising a feed pipe for compressed liquid, a nozzle at the end of the feed pipe, a sand trap below the nozzle, and a valve movable within the feed pipe above the sand trap and adapted to shut the opening of said nozzle.

2. A jet washing apparatus for filters comprising a feed pipe for compressed liquid, a nozzle at the end of the feed pipe, a sand trap below the nozzle, and a conical valve movable within the feed pipe above the sand trap and adapted to shut the opening of said nozzle which is shaped to form a seat for said valve.

3. A jet washing apparatus for filters comprising a feed pipe for compressed

liquid, a nozzle at the end of the feed pipe, a sand trap below the nozzle, and a cone shaped valve movable within the feed pipe above the sand trap and adapted to shut the opening of said nozzle, which opening is rounded off at its lower rim to form a seat for said valve the cone shaped valve being of such a length as to reach with its vertex approximately to the mouth of the nozzle in the open position.

4. A jet washing apparatus for filters comprising a feed pipe for compressed liquid, a nozzle at the end of the feed pipe, a sand trap below the nozzle, a valve movable within the feed pipe above the sand trap and adapted to shut the opening of said nozzle, and a valve rod carrying the said valve and adapted to be operated by hand from outside.

5. A jet washing apparatus for filters comprising a bend forming a feed pipe for compressed liquid, a nozzle at the upper end of the bend, a sand trap below the nozzle, a rod passing through said sand trap with one end and out through the wall of the bend with its other end, a valve carried by the first named end of the rod and adapted to shut the opening of said nozzle, and a double armed lever fulcrumed outside on the bend and rotatably connected with the end of the rod projecting out.

6. A jet washing apparatus for filters comprising a feed pipe for compressed liquid, a nozzle at the end of the feed pipe, a sand trap below the nozzle, a valve movable within the feed pipe above the sand trap and adapted to shut the opening of said nozzle, a perforated mantle surrounding the upper end of the feed pipe and constituting an annular space between the feed pipe and the mantle, a conduit connecting the said annular space with the feed pipe and a hand operated valve within said conduit.

7. A jet washing apparatus for filters comprising a feed pipe for compressed liquid, a nozzle at the end of the feed pipe, a sand trap below the nozzle, a valve movable within the feed pipe above the sand trap and adapted to shut the opening of said nozzle, a perforated mantle having inclined noses covering the perforations, and surrounding the upper end of the feed pipe and spaced therefrom to leave an annular space between the feed pipe and the mantle, a conduit connecting the annular space with the feed pipe, and a valve for controlling the conduit.
